DRIVING MECHANISM FOR TALKING FILM APPARATUS

Heinz Küppenbender, Dresden, Germany, assignor to Zeiss Ikon Aktiengesellschaft Dresden, Dresden, Germany

Application July 6, 1934, Serial No. 734,005
In Germany July 19, 1933

1 Claim. (Cl. 271—2.3)

This invention relates to a driving mechanism for use in connection with talking film recording, as well as reproducing apparatuses and is intended especially for small-sized apparatuses, as 5 preferably employed by amateurs, but the invention can nevertheless be employed also in connection with the ordinary large-sized apparatuses as generally used in practice.

In order to obtain sound reproduction free 10 from disturbing oscillations from a talking film it is indispensably necessary to move the film perfectly uniformly past the place where the sound is transmitted from the film to the loud-speaker. The chief causes from which disturbances arise are the members of the driving mechanism, such as cog-wheels, chains, or the like, as well as the sprocket rolls over which the film runs. It has already been endeavored to 15 overcome the disturbances caused by said members by inserting into the driving mechanism fly wheel masses, elastic couplings, and the like, but the effect has not been satisfying, as the disturbing oscillations are not entirely eliminated.

The object of the present invention is to obtain 20 such complete elimination of the disturbing oscillations and perfect reproduction, and in designing the means for attaining this object I have started from the idea that, as the disturbing oscillations come from different sources, it 25 will be necessary to use separate means designed and selected to suit the different sources, or disturbing causes, and so-to-say tuned with respect to them.

The invention is illustrated diagrammatically 30 and by way of example on the accompanying drawing on which Figure 1 is a front-view of a driving mechanism improved according to this invention, and Figure 2 is a side-view of the same.

On the drawing, 1 (Fig. 1) denotes a belt which 35 is driven by an electromotor (not shown) and drives in turn a shaft 2 carrying a rotary diaphragm 16 (Fig. 2) and a small cog-wheel 3 which meshes with a large cog-wheel 17 keyed on a shaft 18 on which a sprocket roll 4 is mounted, over which the film 19 is conducted, as shown in dotted lines and indicated by the two arrows in the upper left-hand corner of Fig. 1.

On the shaft 2 is also a cog-wheel 5 which 40 drives a train of cog-wheels 6, 7, 8 and 9, of which cog-wheels the wheel 9 is keyed on a shaft 20 on which the second sprocket-roll 10 is rigidly mounted. The film runs, of course, also over this roll, as shown, and is also led over a 45 curved pick-up member 11.

The cog-wheel 8 is keyed on a shaft 12 which

also carries a flywheel-mass 13 which constitutes the member doing away with the disturbances produced by the cog-wheels. The weight of this flywheel-mass is so chosen or, in lieu thereof, said flywheel-mass is rotated with such a high 5 number of revolutions, that the disturbances produced by the train of cog-wheels are reflected back into the train itself practically as if coming from a solid wall and are absorbed therein in the form of push energy and friction energy. 10

Furthermore, in order to render innoxious also the fine disturbing oscillations produced by defects of the sprocket roll 10, a roll 14 has been provided which is keyed on a shaft 21 which likewise carries a flywheel-mass 15. The roll 14 15 and the flywheel-mass 15 are not driven by the driving mechanism of the apparatus, but by the friction of the film running over the roll 14.

I wish it to be understood that I do not claim either of the two flywheel-masses singly, as the 20 effect sought to be attained by the present invention, can be attained solely by the simultaneous action of the two flywheel-masses, as has been ascertained by very extended experiments. The effect is practically perfect. It is now possible 25 to run also small-sized taking and reproducing apparatuses, such as generally used by amateurs, without any internal oscillations disturbing the sounds recorded on, or reproduced, from the film. The means by which this favorable 30 effect is attained are cheap, which is likewise important especially for amateurs.

I claim:

An arrangement particularly for small talking film apparatus for eliminating or reducing the 35 mechanical disturbing oscillations of the record carrier for the purpose of obtaining perfect reproduction, comprising in combination a driving means, a diaphragm shaft driven by said means, two pinions on said shaft, a film feeding 40 sprocket roll carrying a gear wheel meshing with one of said pinions, a train of gears meshing with the other of said pinions, a second film feeding sprocket roll rigidly connected with the last gear of said train, a flywheel-mass rigidly 45 connected with one of the intermediate gears of said train and driven at a higher speed than said last mentioned sprocket roll to eliminate the fundamental disturbing frequencies produced by said train, an independent film guiding roll, and a 50 second fly-wheel mass rigidly connected with said guiding roll and adapted to be rotated by the film to eliminate the higher disturbing frequencies produced by the film running over said sprocket rolls.

HEINZ KÜPPENBENDER.
